DESIGN FOR A RADIOCABINET

Richmond L. Chipman, Jr., Montclair, N. J., assignor to Bakelite Corporation, New York, N. Y., a corporation of Delaware

Application April 2, 1935, Serial No. 56,179

Term of patent 3½ years

To all whom it may concern:

Be it known that I, Richmond L. Chipman, Jr., a citizen of the United States of America, residing at Montclair, in the county of Essex and State of New Jersey, have invented a new, original, and ornamental Design for a Radiocabinet, of which the following is a specification, reference being had to the accompanying drawing, forming part thereof.

Fig. 1 is a front view of a radiocabinet showing my new design;

Fig. 2 is a side view of the radiocabinet;

Fig. 3 is a top view of the radiocabinet.

The dominant features of the design reside in the grille and tuning dial section and the columns.

The drawing is shaded to show the contrasting effect.

I claim:

The ornamental design for a radiocabinet, as shown and described.

In testimony whereof, I affix my signature.

RICHMOND L. CHIPMAN, JR.
